(57) CLAIM

The ornamental design for a golf club head, as shown and described.

DESCRIPTION

FIG. 1 is a rear, heel-side, bottom perspective view of the golf club head;

FIG. 2 is a rear, bottom perspective view thereof;

FIG. 3 is a bottom plan view thereof;

FIG. 4 is an enlarged view of area 4 in FIG. 1;

FIG. 5 is a cross-sectional view thereof taken a long line 5-5 in FIG. 3; and,

FIG. 6 is an enlarged view of area 6 in FIG. 5.

The broken lines depict either unclaimed portion of the golf club head or enlargement areas, and thus form no part of the claimed design. The dot-dash chain lines depict boundaries of the claimed subject matter, and thus form no part of the claimed design.

1 Claim, 5 Drawing Sheets(56)
